UNITED STATES PATENT OFFICE

REUBEN LEVINSON, OF GOODMANES, GREAT BRITAIN

CONSTRUCTION OF WRIST SPLINTS

Application filed August 27, 1928, Serial No. 302,392, and in Great Britain April 17, 1928.

This invention relates to wrist splints, more especially to wrist splints of the Carr type. In the usual Carr splints the hand or finger grip is fixedly mounted upon the head of the splint at one side thereof, the head of the splint being cut at an angle and the splint being recessed or shaped at the side at which the hand or finger grip is provided to accommodate the thenar eminence. Consequently, a splint for the right hand cannot be used for the left hand and it is necessary that both right and left hand splints should be available as required.

The present invention has among its objects to provide an improved construction of wrist splint which is equally effective for use either with the right hand or with the left hand.

According to the invention a wrist splint, which may be constructed as is usual of V-shaped cross-section, is recessed or shaped near the head on both sides for the accommodation of the thenar eminence and the hand or finger grip of suitable form is fitted upon the head of the splint in such manner that it may be disposed at one side or the other thereof as required for use with the right hand or with the left hand. Thus, the hand or finger grip may be hinged to the head of the splint in any suitable manner or may be otherwise attached thereto so that its position with respect to the splint may be reversed from one side to the other. The splint is preferably constructed of wood, but may be constructed of any other suitable substance.

The invention is hereinafter described by way of example with reference to the accompanying diagrammatic drawings, in which:—

Figure 1 is a side elevation of a construction of wrist splint according to the invention;

Figure 2 is a cross-section on the line 2—2 of Figure 1;

Figure 3 is a section on the line 3—3 of Figure 1, showing the hand or finger grip turned into a position at one side of the splint;

Figure 4 is a view similar to Figure 3 illustrating a modification; and

Figure 5 is a similar view illustrating a further modification.

In carrying the invention into effect according to one construction and with reference to Figures 1, 2 and 3 of the accompanying diagrammatic drawings, the splint may be constructed of wood and the main part *a* thereof may be of triangular cross-section as indicated in Figure 2, while the head or front part of the splint may be cut away or shaped at each side to form a recess *a'* adapted for the reception of the thenar eminence, the opposite faces of the reduced part of the splint being, for example, substantially parallel. The head or front part of the splint is cut at an angle in the usual manner and a hand or finger grip *b* is hinged upon the inclined end of the splint so that it may be swung from one side to the other as indicated in dotted lines in Figure 3. In the construction illustrated a continuous hinge member *c*, formed by bending a strip of sheet metal, is inserted into a slot *a* in the head or front end of the splint and, if necessary, is held therein by means such as screws *a* extending transversely through the splint and through corresponding holes in the hinge member *c*. A length of stout wire adapted to be received within the hinge member *c* is bent so that its ends *d* are parallel disposed and at right angles to the hinge, the ends *d* being driven or otherwise fixed into the hand or finger grip *b* so that thus the latter is hingedly mounted upon the head or front end of the splint *a*. Preferably, the hinge connection is so arranged that when the hand or finger grip *b* is moved to a position at one side of the splint, it comes into contact with the adjacent surface of the reduced part of the splint so as to be firmly supported against the tension imposed when the hand or finger grip is engaged by the hand or fingers in use.

In an alternative construction, as illustrated in Figure 4, the hinge hereinbefore described may be replaced by a flat strip *e* of rigid, flexible, resilient or readily bent material fitted into slots respectively in the hand or finger grip *b* and in the head or front end of the splint *a* being secured in position within the slots, if required, by means such as

screws. In the case in which the strip is provided of rigid material it is initially bent to the cross-sectional form shown in the drawing, the position of the hand or finger grip being reversed by withdrawing the strip *e* from engagement with the slot in the splint *a*, turning the hand or finger grip *b* over end for end and reinserting the strip *e* into the slot in the splint. When the strip *e* is constructed of flexible, resilient or readily bent material, it may be permanently fixed in the respective slots, it being understood that in this case the strip *e* serves as a hinge.

According to a further modification, as illustrated in Figure 5, the inclined head or end of the splint *a* may be fitted with a transverse strip *f* extending laterally beyond the lateral faces of the head of the splint and formed at its edges with beads *f'*, flanges or the like adapted to engage with corresponding slot or recess in the hand or finger grip *b* which thus may be applied at one side or the other of the head by sliding upwardly or downwardly into position. The flanges *f'* and the corresponding slot in the hand or finger grip *b* may be slightly tapered or other means may be provided to avoid relative axial movement of the parts when the splint is in use. Any equivalent arrangement of slidably engageable parts may be provided.

It will be understood that any other suitable construction of hinge or reversible connection between the hand or finger grip and the splint may be provided.

35. What we claim is:—

1. A wrist splint comprising a splint member shaped on both sides for application alternatively to the right hand or to the left hand, and having its forward edge cut at an angle, said angular edge having a slot, a hand grip, a sheet metal hinge member fitted into the slot in the edge of the splint, and means including a stout wire extending through the hinge member and having its ends bent to engage with the said hand grip to enable the latter to be disposed on either one of the opposite side surfaces of the splint as required.

2. A wrist splint including a splint member shaped on the opposite surfaces to adapt one surface for use with the right hand and the other surface for use with the left hand, a hand grip, and means to connect the hand grip with the splint member to enable the hand grip to be bodily moved to a position wholly above and in substantial contact with either surface of the splint member selected for use.

3. A wrist splint including a splint member shaped on the opposite surfaces to adapt one surface for use with the right hand and the other surface for use with the left hand, a hand grip, and means to connect the hand grip at a fixed angle and for bodily movement relative to the splint member, said means pro-

viding for complete bodily movement of the hand grip to a position above and in substantial contact with a selected surface of the member while maintaining the predetermined angular relation with such member.

4. A wrist splint including a splint member shaped on the opposite surfaces to adapt one surface for use with the right hand and the other surface for use with the left hand, a hand grip, and a hinge connecting the hand grip with the splint member to enable the hand grip to be bodily moved to a position wholly above and in substantial contact with either surface of the splint member selected for use.

5. A wrist splint including a splint member shaped on the opposite surfaces to adapt one surface for use with the right hand and the other surface for use with the left hand, a hand grip, and an element fixed to the end of the splint member and formed at its respective ends with means to cooperate with and support the hand grip, said element having its respective ends arranged beyond the respective surfaces of the splint member whereby with the hand grip in cooperation with a particular end of such element, the hand grip is disposed wholly above and in substantial contact with the selected surface of the member.

6. A wrist splint including a splint member having the main portion of its length of substantially triangular form in cross section, the forward portion of the member being cut away to present a section of substantially uniform thickness through its width, the free edge of such cut-away portion being inclined with respect to the longitudinal median line of the member, and hand grip, and means connecting the hand grip to said inclined edge of the member to provide for bodily movement of the hand grip to a position above and substantially in contact with the member adjacent such inclined edge while maintaining the angular relation between the hand grip and member.

In testimony whereof I have hereunto signed my name.

REUBEN LEVINSON.
